UNITED STATES PATENT OFFICE.

ALLEN JAMES ACKER, OF OGDENSBURG, NEW YORK.

PACKAGE ATTACHMENT FOR LOOSENING PACKED MATERIAL.

1,263,306.

Specification of Letters Patent. Patented Apr. 16, 1918.

Application filed April 18, 1917. Serial No. 163,072.

To all whom it may concern:

Be it known that I, ALLEN JAMES ACKER, a citizen of the United States, and a resident of Ogdensburg, in the county of Saint 5 Lawrence and State of New York, have invented a certain new and useful Improvement in Package Attachments for Loosening Packed Material, of which the following is a specification.

10 The present invention relates to packages, particularly adapted for containing tobacco and the like which is tightly compressed or packed in the package.

An object of the present invention is to 15 provide a package of this character with an attachment which may be carried as a part thereof, and which may be manipulated for loosening the material packed to admit of the ready removal thereof.

20 The invention further aims at the provision of a relatively small and economically constructed and applied attachment for tobacco cans and the like which may be carried in the can between the inner wall thereof and the wrapper or lining placed in the can about the compressed material, and which is flexibly connected to the can to admit of the withdrawal of the attachment and the free manipulation thereof to loosen 25 the material, particularly when the package 30 or can is partly emptied.

The above, and various other objects and advantages of this invention will be in part described, and in part understood, from the 35 following detailed description of the present preferred embodiment, the same being illustrated in the accompanying drawing wherein:

Figure 1 is a perspective view of a tobacco can open, showing the attachment of 40 this invention applied thereto and applied to the material for loosening the same.

Fig. 2 is a side elevation of the same, partly in section, disclosing the attachment packed and sealed in the can.

45 Fig. 3 is a fragmentary sectional view taken transversely through the upper end of the can showing the attachment packed therein.

Referring to this drawing, A designates 50 the body of a can or package adapted to contain material B, such as tobacco, and provided with a closure C adapted to be closed over the open end of the body A and sealed in closed position by a sealing strip 55 D which may be a revenue stamp, in the usual manner.

The body or container A is provided with a liner E in the form of a wrapper adapted to contain the material B.

The attachment is in the form of a prod 60 10 which may comprise a length of relatively stiff wire pointed at one end, as at 11, and being flattened and perforated at its opposite end 12 to receive one end of a cord 13, or other flexible member which is provided with a knot 14 adapted to hold the cord from removal from the end 12.

The opposite end of the cord 13 is preferably threaded through an opening formed in the cover C, and the latter is preferably 70 depressed at such point to provide a seat or pocket 15 for the reception of a knot 16 which is formed upon said opposite end of the cord 13 for retaining the latter from withdrawal from the cover C. Preferably, 75 the seat 15 with the aperture in the bottom thereof is formed intermediate the ends and lateral edges of the cover C, and the sealing strip D is pasted or otherwise suitably secured over the cover C in the usual manner, 80 and over the seat 15 and the knot 16, to inclose the latter and prevent the accidental raising of the knot 16 out of the seat.

The prod 10 is of a length equal substantially to the height of the box or body 85 A, and is adapted to be placed therein between the inner wall of the body and the adjacent side of the liner E, with the apertured end 12 of the prod at the upper end of the receptacle. The cord 13 is looped 90 upon itself and placed on top of the liner E immediately beneath the cover C, as shown in Fig. 2, and the free end of the cord 13 may be projected downwardly into the receptacle A between the wall thereof 95 and the adjacent side of the liner E, as shown in Fig. 2, for the purpose of distributing the cord through the package, and to prevent tangling of the same at the top.

When the sealing strip D is broken and 100 the cover C is raised, the user may grasp the looped part of the cord 13 and draw the same upwardly to remove the prod 10 from the package. The prod 10 may now be grasped in the hand in any suitable manner, as shown in Fig. 1, and the point 11 thereof applied to the packed material for loosening the same. The prod 10 is of especial advantage when the packed material B is partially consumed so that access to 110 the lower end of the can cannot be readily had by the finger or ordinary instrument

or device. In this case the prod 10 is grasped at its upper end and inserted downwardly into the body A of the package and into contact with the material B.

- 5 By connecting the prod 10 to the body or cover of the package by means of the flexible connector 13, the prod 10 may be manipulated freely for loosening the packed material, and cannot be lost or detached 10 from the can. The prod 10 is adapted to be inserted back into the can A after use, and the flexible cord 13 affords a ready means for drawing the prod upwardly from between the adjacent walls of the can and 15 the lining E.

It is of course understood that the prod 10 may be given any suitable shape or form found desirable in the manufacture and packing thereof, and any suitable flexible 20 connector may be employed without departing from the spirit of this invention, and being restricted only by the scope of the following claims:

I claim:-

- 25 1. The combination with a can, a wrapper therein adapted to contain packed material, a cover to close the can, and a sealing strip secured to the can over the cover, of a prod adapted for insertion in the can between 30 the same and the wrapper and being of a length to lie wholly within the can beneath

the cover when closed, a cord secured at one end to the prod, said cord extending at its other end through the cover from the inner side thereof and being knotted with 35 the knots lying beneath the sealing strip, said cord when the cover is closed being adapted to lie between the top of the wrapper and the can, and the cover when opened being adapted to raise the end of the cord 40 for easy grasping to withdraw the prod.

2. A device as specified comprising a can adapted to contain a wrapper with packed material therein, a cover adapted to close the open end of the can and provided intermediate with a depressed apertured seat, a cord engaging at one end through the aperture in the cover and provided with a knot adapted to fit into said seat, a sealing strip adapted for securing over the cover and 50 over said seat to inclose the knot and hold the latter to the seat, and a prod adapted for engagement between the wall of the can and the adjacent side of the wrapper and being pointed at one end for engagement in the packed material to loosen the same and having an eye in its opposite end for the reception of the opposite extremity of said cord, said opposite extremity of the cord being provided with a knot for engagement 55 with the prod to retain the cord therein.

ALLEN JAMES ACKER.
